UNITED STATES PATENT OFFICE.

CHARLES F. OSGOOD, OF CLAREMONT, NEW HAMPSHIRE, ASSIGNOR TO SULLIVAN MACHINERY COMPANY, A CORPORATION OF MASSACHUSETTS.

MINING MACHINE.

Application filed June 18, 1923. Serial No. 646,000.

My invention relates to mining machines.

An object of my invention is to provide an improved mining machine. Another object of my invention is to provide improved cutting and feeding mechanism for a mining machine. A further object of my invention is to provide an improved feeding and feed controlling mechanism for a mining machine whereby the operation of the machine is materially improved and the mechanism simplified and more flexible to operate. These and other objects of my invention will hereinafter more fully appear.

In the accompanying drawings I have shown for purposes of illustration one embodiment which my invention may assume in practice.

In these drawings,—

Fig. 1 is a side elevation of a mining machine of the flexibly fed type mounted on its truck in position for transport.

Fig. 2 is a side elevation of the opposite side of the mining machine shown in Fig. 1.

Fig. 3 is a plan view, partially in section, of Fig. 2.

Fig. 4 is a side elevation, partially in section, of the mechanism shown in Fig. 3.

Fig. 5 is a detail sectional view taken on line 5—5 of Fig. 3.

Fig. 6 is a diagrammatic view showing the machine in operation in a room.

In this illustrative construction I have shown a mining machine of the room and pillar type comprising a casing 1 slidably on a bottom plate 2 on the mine bottom and movable relative to a feeding means adapted to provide advance flexible feeding portions, herein a continuous flexible feeding member 3 in the form of a chain, and having a cutter bar 4, rigidly secured within said frame, provided with an endless cutter bit carrying chain 5. The feeding means and the cutting mechanism are driven from a suitable motor 6 (indicated by dotted lines) through driving connections, hereinafter described, and connected to a feed operating member 7 and a take-up member 7' disposed on a horizontal axis and projecting laterally from the rear end of the frame, and to a cutter chain sprocket 8 rotatable on a vertical axis beneath the rear end of the machine frame.

In describing my improved construction, I will first describe the cutter chain driving mechanism. This, being the invention of

one Morris P. Holmes, need not be described specifically. It will be noted, however, that the armature shaft of the motor 6 is provided with a bevel pinion 9 which in turn meshes with a bevel gear 10 journaled on a bearing 11 about a vertically disposed stud 12 on the rear end of the machine frame. The gear 10 is connected, as by bolt and nut connections 13, to a sleeve carrying a pinion 14 which meshes with a plurality, herein three, of planetary gears 15, journaled in suitable bearings on a spider 16, only one of these gears being shown. The planetary gears mesh with an internal gear 17 attached as by screws 18 to the cutter chain sprocket 8 and which with the sprocket is journaled in bearings 19 herein located between bearings 20, so as to rotate relative to the spider and the lower end of the stud. As shown, the spider 16 is also provided with an up-standing sleeve 21 journaled on the stud inside of the sleeve carrying the pinion 14, and suitable bearing sleeves 22 and 23 are provided on the opposite sides of the sleeve 21 while the bearings 19 are enclosed in sleeves 24 and 25. A flanged ring 26 is interposed between the lower bearing 19 and the bearing 20, while a retaining member 27, attached to the bottom plate by screws 28 and to a reduced portion 29 on the stud by a screw 30, is provided to hold the parts in assembled relation. The gear 17 is provided with a friction surface 31 on its outer periphery with which a brake band 32 cooperates under the control of a hand-wheel 33.

Cooperating with this mechanism is the feeding mechanism. This mechanism is herein connected to and driven by the sleeve 21 on the spider 16, the same being connected by a semi-permanent clutch 34 to a sleeve 35 having a worm 36 formed thereon, the sleeve 35 in turn being journaled on a flanged bearing sleeve 37, the bearing 11, and a bearing 38 removable through the top of the machine frame upon removal of a cap 39. This worm 36 meshes with a worm gear 40 disposed on a transverse horizontal axis herein as preferably coaxial with members 7 and 7'. As shown, the worm gear 40 is keyed, as at 41, to a shaft 42 which has a pinion 43 formed thereon adapted to mesh with a plurality of planetary gears 44 (Fig. 5) suitably journaled on a spider 45 keyed to the feed op-

erating member 7, as at 46. The planetary gears also mesh with an internal gear 47 suitably journaled on bearings on the shaft 42 and provided with a friction surface 48 on its outer periphery under the control of a brake band 49, operated through suitable controlling mechanism, hereinafter described. As shown, the worm gear 40 is also keyed, as at 50, to a shaft 51, oppositely disposed with respect to the shaft 42, and having similar planetary connections including a pinion 52 formed thereon which meshes with a plurality of planetary gears 53, suitably journaled on a spider 54 keyed to a take-up member 7' similar to feed operating member 7. The gears 53 mesh with an internal gear 56, journaled in suitable bearings on the shaft 51, and having a friction surface 57 on its outer periphery under control of a brake band 58. The worm gear 40 is also provided with a friction surface 59 under the control of a brake band 60, herein-after described. The brake bands 49, 58, and 60 are each operated through a suitable toggle mechanism 61, one only being shown herein, by means of controlling levers 62, 63, and 64 (Fig. 2), respectively, adapted to be carried on either side of the machine.

Cooperating with the feeding mechanism and engaging both the feed operating member 7 and the take-up member 7' is the flexible feeding member or chain 3. Herein, the machine is shown as adapted to cut from right to left and in this disposition of the parts, it will be noted that the advancing portion of the chain 3 extends from the top of the feed sprocket 7, down beneath an idler sprocket 65 and forward toward the front end of the machine and around an idler 66 laterally to a jack A, while the receding portion extends downward beneath an idler 69, then upwardly towards the top of the machine, then transversely across the latter in a guiding channel 70, then forwardly about the take-up sprocket 7', and then around guides 71 and 72 rotatable on upstanding axes on the rear end of the frame, and laterally to a jack B. Obviously, by reversing the arrangement of the idler sheave 65, the chain 3, and the control levers 62, 63 and 64, the machine may cut from left to right. It will also be understood that the machine is adapted to be transported on a truck 73 and drive the latter, the truck driving and controlling mechanism herein being provided by the feed and feed controlling mechanism previously described and operatively connected to the truck wheels through a chain, herein a short section of chain 74 similar to the feed chain. Attention is also directed to the fact that this chain 74 may be connected if desired between either the feed operating member 7 or the take-up member 7' and the truck wheels, the idler 65 being removed when necessary.

In the operation of my improved construction the machine is preferably, when unloaded from its wheeled truck 73, brought up to the face to the position indicated in full lines in Fig. 6. The advancing portion 70 of the flexible member 3 is then connected to the left hand rib while the receding portion is connected to the right hand rib, to the jacks A and B, respectively. The motor is then started, and when up to speed, the brake 75 band 32, under control of hand wheel 33, is applied tending to hold the internal gear 17 from rotating and slowly rotating the sprocket 8 until the cutter chain 5 is resisted by the coal, whereupon the feeding member 7 80 and the take-up member 7' are caused to rotate slowly. Then through suitable manipulation of the levers 62 and 63 controlling the brake bands 49 and 58, the cutter bar is sumped in under the coal as indicated by 85 dotted lines at the right of Fig. 6, the band 32 being released at this time, and the take-up member 7' slowly taking in the chain while the feed member 7 slowly pays it out and the slack chain moves in the channel 70. During this operation, the speed of the feed and take-up members is entirely under the control of the brake band 60 reacting back 90 through the driving mechanism to the cutter chain 5, which is resisted by the coal. When 95 in this position the machine may be straightened up and then cut transversely across the face, as indicated by the next dotted line position at the left. When the machine reaches the left hand rib it may be inclined relative to the rib, as shown by the last dotted line position, and backed out without removing the jack A, by suitable manipulation of brake bands 49 and 58 and returned to the truck at a high or haulage speed like- 100 wise under control of the brake band 60. In the operation of my improved mechanism, it will be noted that by means of the band 32 the chain driving sprocket 8 may be rotated or caused to remain idle while the 105 motor is running, and that the speed of this sprocket is controlled by the amount of application of the brake band 60 while the cutter chain drive is coordinated with the feeding mechanism. Attention is also directed 110 to the fact that by suitable manipulation of the brake band 60 it is possible to vary the speed of the feed operating member 7 or the take-up member 7', either independently or 115 simultaneously by means of brake bands 49 and 58 and thereby increasing the facility of operation of the machine. The transport truck 73, which may be driven by either the feed member or the take-up, herein the take-up member 7', through the chain connection 120 74, may also have its speed controlled by the application of brake band 60, the cutter chain being held stationary at this time by means of brake band 32, so that a relatively 125 high truck speed may be obtained. 130

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a mining machine, a frame slidable on its bottom on the mine bottom during cutting and having cutting mechanism projecting from one end thereof, a motor driving said cutting mechanism, variable speed mechanism driven wholly by said motor and having a terminal element rotatable by said motor at different speeds, and feeding means disposed to the rear of said cutting mechanism and driven by the terminal element of said variable speed mechanism, said feeding means including a plurality of independent planetary gearings and being operable to feed said machine in a direction parallel to the working face during cutting.

2. In a mining machine, a frame slidable on its bottom on the mine bottom during cutting and having cutting mechanism projecting from one end thereof, a motor driving said cutting mechanism, variable speed mechanism driven wholly by said motor and having a terminal element rotatable by said motor at different speeds, and feeding means disposed to the rear of said cutting mechanism and driven by the terminal element of said variable speed mechanism, said feeding means including a plurality of independent friction controlled planetary gearings and being operable to feed said machine in a direction parallel to the working face during cutting.

3. In a mining machine, a frame slidable on its bottom on the mine bottom during cutting, cutting mechanism projecting therefrom at one end thereof, a motor, fast and slow speed mechanism driven thereby, and feeding means disposed to the rear of said cutting mechanism and operative to effect feeding of said machine in a direction parallel to the working face during cutting, said feeding means including a plurality of independent planetary gearings transmitting power during such feed.

4. In a mining machine, a frame, cutting mechanism projecting from one end thereof and including a cutter chain driving sprocket, a motor, variable speed mechanism driven by the motor, and feeding means driven by the mechanism including a feed operating member rotating on an axis disposed to the rear of the axis of rotation of the cutter chain driving sprocket, a take-up member, and friction controlled planetary gearings individual to said feed operating member and to said take-up member respectively.

5. In a mining machine, a motor, variable speed mechanism driven thereby, and feeding means driven by said mechanism including a feed operating member and a take-up member, and a plurality of friction controlled planetary gear mechanisms one individual to each of said members.

6. In a mining machine, cutter chain driving mechanism, feeding mechanism including driving gearing dependent for rotation upon the resistance to movement of the cutter chain and also including a plurality of independent planetary driving mechanisms, and means whereby variation of the resistance to movement of the cutter chain may be effected at the will of the operator.

7. In a mining machine, a cutter chain, planetary driving mechanisms, driving gearing for said chain and driving mechanisms operatively connecting the same so that rotation of said driving mechanisms is dependent upon resistance to rotation of said cutter chain, said gearing including a friction controlled element, and feed operating and take-up members each operatively connected to a different one of the planetary driving mechanisms.

8. In a mining machine, cutter chain driving mechanism including a friction controlled element, a plurality of planetary driving mechanisms, feed operating and take-up members operatively connected to said mechanisms, and independent controlling means for said members for effecting independent control thereof.

9. In a mining machine, feeding mechanism including a plurality of relatively rotatable feed controlling elements each adapted to effect machine movement, separate frictionally controlled planetary gear trains one associated with each of said elements, and means whereby said elements may be driven at different speeds through their respective planetary trains.

10. In a mining machine, feeding mechanism including feed operating and take-up members, separate planetary gear trains one associated with each of said members, and means whereby said members may be driven at different speeds through their respective planetary trains.

11. In a mining machine, feeding mechanism including feed operating and take-up members, planetary gear trains associated one with each of said members, and means whereby said members may be driven at different speeds through their respective planetary trains, said means including frictional means associated therewith.

12. In a mining machine, cutting mechanism including a cutter chain driving sprocket, feeding mechanism including feed controlling elements adapted to cooperate directly with flexible feeding means, independent planetary gearings, a motor for

- driving one of said elements of said mechanism through one of said gearings and the other through the other, and means disposed between said motor and gearing whereby said elements may be driven at different speeds including a member coaxial with said cutter chain driving sprocket.
13. In a mining machine, feeding mechanism including feed controlling elements adapted to cooperate directly with flexible feeding means, independent planetary gearings one associated with one and another with another of said feed controlling elements, a motor for driving an element of said mechanism through said gearing, and means disposed between said motor and gearing whereby said elements may be driven at different speeds, said latter means including a worm gear disposed on a vertical axis and a worm wheel coaxial with one of said elements.
14. In a mining machine, cutting mechanism including a cutter chain driving sprocket, feeding mechanism including feed controlling elements adapted to cooperate directly with flexible feeding means, independent planetary gearings one associated with one and another with another of said feed controlling elements, a motor for driving an element of said mechanism through said gearing, and means disposed between said motor and gearing whereby said members may be driven at different speeds including a member coaxial with said cutter chain driving sprocket, said planetary gearings being disposed to one side and the other to the other side of the longitudinal axis of said machine.
15. In a mining machine, cutting mechanism including a cutter chain driving sprocket, driving mechanism therefor, feeding mechanism for said machine including feed controlling elements adapted to cooperate directly with flexible feeding means, planetary gearing including planetary gearings each individual to one feed controlling element and adapted to be frictionally controlled independently of said driving mechanism, a motor, and means whereby at least one of said elements may be driven at different speeds through said gearing by said motor including an element coaxial with said cutter chain driving sprocket.
16. In a mining machine, a motor, feeding mechanism including gearing, mechanism for rotating the latter at a plurality of speeds while the motor speed remains constant, feed operating and take-up members, and operative connections between said gearing and said members including frictionally controlled planetary gearings respectively individual to each of said members.
17. In a mining machine, a motor, feeding mechanism including gearing, mechanism for rotating the latter at a plurality of speeds while the motor speed remains constant, feed operating and take-up members, and operative connections between said gearing and said members including frictionally controlled planetary gearings respectively individual to each of said members.
18. The combination with a mining machine having a motor, of worm gearing rotatable at different speeds while the motor speed remains constant, a plurality of planetary driving mechanisms driven thereby, feed operating and take-up members driven by said planetary mechanisms, and flexible feeding means cooperating with said members.
19. In a mining machine, cutter chain driving mechanism, and feeding mechanism for effecting feed of said machine in a direction parallel to a working face during cutting including a plurality of independent planetary driving mechanisms and driving means for the latter including means driven from the cutter chain driving mechanism and dependent upon the reaction of the cutter chain for its operation.
20. In a mining machine, cutter chain driving mechanism, and feeding mechanism for effecting feed of said machine in a direction parallel to a working face during cutting including a feed operating member, a take-up member, and a plurality of frictionally controlled planetary driving mechanisms for said members, one individual to each of the same, and driving means for the latter including means driven from the cutter chain driving mechanism and dependent upon the reaction of the cutter chain for its operation.
21. In a mining machine, cutter chain driving mechanism, lateral feeding mechanism including means dependent upon the reaction of said cutter chain for operation and further including a plurality of separate planetary driving mechanisms, and means independent of said planetary driving mechanisms for controlling said feeding mechanism.
22. In a mining machine, cutting mechanism, driving means therefor, feeding mechanism for said machine including feed operating and take-up members, planetary gearing, a motor for driving one of said members through said gearing, and means frictionally controlled independently of said feeding mechanism whereby said members may be driven wholly independently of each other at different speeds.
23. In a mining machine, cutter chain driving mechanism, feeding mechanism therefor including a feed operating member and a take-up member, planetary driving means for said members including planetary gearing individual to each of said members respectively, and means to drive said members independently or simultaneously and in either case at variable speeds.

24. In a mining machine, cutter chain driving mechanism, feeding mechanism therefor including feed operating and take-up members, planetary driving mechanisms therefor, one individual to each of the same, and means to drive said planetary driving mechanisms and so said members at variable speeds in the same direction.
25. In combination with a mining machine, of a transport truck therefor, machine feeding mechanism including a feed operating member and a take-up member, planetary driving mechanism for said members, and means to drive said truck at variable speeds from one of said members.
26. In a mining machine, a feed operating member adapted to cooperate directly with flexible feeding means, planetary gearing, a motor, and means whereby said motor can drive said member at a plurality of speeds, said latter means including a plurality of mutually independently frictionally controlled means disposed between said motor and planetary gearing.
27. In a mining machine, a frame, cutting mechanism projecting from one end thereof, feed operating means therefor disposed at the opposite end thereof including a feed operating member adapted to cooperate directly with flexible feeding means, and actuating means therefor including planetary gearing, a motor, and means between said gearing and motor whereby said motor can drive said member at different speeds, said means including a plurality of mutually independently frictionally controlled elements disposed between said motor and gearing.
28. In combination, a mining machine, a transport truck therefor, machine feeding means including a plurality of feed controlling elements each adapted to cooperate directly with flexible feeding means, and means whereby said truck may be driven from each of said elements.
29. In combination, a mining machine, a transport truck therefor, a plurality of variably controllable feed controlling elements carried by said mining machine and each adapted to cooperate directly with flexible feeding means, and means whereby each of said elements is adapted to control movement of said truck.
30. In combination, a mining machine, a transport truck therefor adapted to longitudinally slidably receive said mining machine, a plurality of feed controlling elements carried by said machine each of which is adapted to cooperate directly with flexible feeding means, and means whereby each of
- the same is adapted to drive said truck when said machine is in its transport position.
31. In a mining machine, feeding means for said machine including a feed member and a take-up member, a driving motor therefor, and means to speed up or slow down said members independently without disconnecting the same from said motor.
32. In a mining machine, feeding means for said machine including a plurality of feeding members each adapted to effect machine movement, a driving motor therefor, and means whereby the members may be allowed to speed up or slow down independently without disconnecting the same from said motor.
33. In a mining machine, feeding means for said machine including a plurality of feeding members each adapted to effect machine movement, a driving motor therefor, and means whereby the members may be allowed to speed up or slow down independently without disconnecting the same from said motor, said means including planetary gearing.
34. In a mining machine, feeding means for said machine including a plurality of feeding members each adapted to effect machine movement, a driving motor therefor, and means whereby the members may be allowed to speed up or slow down independently without disconnecting the same from said motor, said means including friction controlled planetary gearing.
35. In a mining machine, cutting mechanism carried thereby, feeding mechanism therefor including a plurality of feed controlling elements each adapted to effect machine movement, a motor, means whereby the same is adapted to drive said mechanisms from a single end thereof, and means whereby said elements may be independently speeded up or slowed down without disconnecting the same from said motor.
36. In a mining machine, cutting mechanism projecting from one end thereof, feeding mechanism therefor including a plurality of feed controlling elements each adapted to cooperate directly with flexible feeding means, a motor, means whereby the same is adapted to drive said mechanism from a single end thereof, and means disposed at the end of said machine opposite to said cutting mechanism whereby said elements may be independently speeded up or slowed down without disconnecting the same from said motor.

In testimony whereof I affix my signature.
CHARLES F. OSGOOD.
